UNITED STATES PATENT OFFICE.

WILLIAM S. WITTER, OF TOLEDO, IOWA.

DESIGN FOR A SPARK-PLUG.

47,941.

Specification for Design.

Patented Oct. 5, 1915.

Application filed July 15, 1914. Serial No. 851,182. Term of patent 7 years.

To all whom it may concern:

Be it known that I, WILLIAM S. WITTER, a citizen of the United States, residing at Toledo, in the county of Tama and State of Iowa, have invented a new, original, and ornamental Design for a Spark-Plug, of which the following is a specification, reference being had to the accompanying drawing, forming part thereof, and wherein—

Figure 1 is an elevational view of a spark

plug embodying my design; and Fig. 2 is an elevational view taken at substantially ninety degrees to Fig. 1.

I claim:

The ornamental design for a spark plug, as shown.

WILLIAM S. WITTER.

Witnesses:

W. A. DEXTER,

L. F. BENESH.
